UNITED STATES PATENT OFFICE.

PAUL HANSON, OF ST. PAUL, MINNESOTA.

GRAIN-BINDER.

SPECIFICATION forming part of Letters Patent No. 379,953, dated March 27, 1888.

Application filed July 14, 1886. Serial No. 207,978. (No model.)

To all whom it may concern:

Be it known that I, PAUL HANSON, a citizen of the United States, residing at St. Paul, in the county of Ramsey and State of Minnesota, have invented certain new and useful Improvements in Grain-Binders, which are set forth in the following specification, reference being had to the accompanying drawings, forming a part thereof.

10 The purpose of this invention is to provide improved mechanism for actuating and releasing the compressor of a grain-binder which shall be more simple in construction and less liable to derangement than is now in common use.

15 In the drawings, Figure 1 is a rear elevation of such parts of a binder-frame and operating mechanism as relate directly to my invention, shown in the position of rest. Fig. 2 is a similar view, the parts being shown in position for discharging the bundle. Fig. 3 is a plan of the parts in position of Fig. 1. Fig. 4 is a section through *xx*, Fig. 3, looking rearward. Fig. 5 is a detail axial section 20 through the link which connects the compressor to its actuating-lever.

25 A A A A A are portions of the binder-frame. B is the needle or band-carrying arm.

C is the compressor.

30 D is a lever which is pivoted on the needle rock-shaft in front of the needle.

E is a link which connects one end of said lever to the compressor.

35 F is a spring coiled around said link and stopped at one end by an adjustable shoulder on said link and at the other end by the end of the lever D. This spring is hereinafter called the "compressor-spring," because the compressor is by it sustained against the bundle, and its tension determines the degree of pressure exerted by the compressor.

40 G is a dog pivoted on a lug of the binder-frame, and G' is a torsion-spring fixed at one end to the frame at some little distance forward of the pivot of the said dog, and by its rear end engaging the dog, as by entering the hole *g* in the latter. This spring tends to resist movement of the dog in either direction on its pivot and to restore it to the position 45 shown in Fig. 1.

The compressor is connected to the needle

eccentrically as to the heel B' of the needle, as is customary.

The link E is connected to the lever D by passing through it near the end (the aperture 55 *d*, which is provided for that purpose, being elongated to allow the movement between the said parts, which will hereinafter appear necessary) and being provided with the stop-nut E' outside said lever.

60 The lever D at the end opposite that at which the link E is connected has on the front side the abutment D', which may be provided with the anti-friction roll D¹⁰, as shown, and said roll bears against the lower end of the 65 dog G, (the periphery *g*² of said end being eccentric to the pivot of the dog, for a purpose hereinafter explained.) The dog G has three branches, G', G², and G³. The branch G² projects downward and forms a stop against 70 which the roll D¹⁰ engages to prevent the lever D rocking on the pivot except at the proper time. The branch G' projects upward and outward and bears against the hub of the lever D and prevents the dog rocking on the pivot too far in 75 that direction, and the branch G³ projects inward and has the abutment G³⁰ jutting slightly rearward.

75 The needle has the tail B² projecting from its back edge and terminating in the lip B²⁰, 80 which extends forward of the vertical plane of the needle, so that it collides with the abutment G³⁰ of the dog G when the needle rises to encircle the bundle.

85 On the lever D, a short distance outward from the abutment D', is the abutment D², jutting rearward across the vertical plane of the needle, so that the back edge of the latter collides with it as it recedes and bears against it while the binder is inactive.

90 The operation is as follows: When the binder is tripped into action, the needle rises and draws the compressor toward the bundle in the usual manner. It will be noticed that the outer end of the compressor is upheld by the 95 spring F, whose lower end rests on the outer end of the lever D and whose upper end bears against the adjustable shoulder or nut E' of the link E, which is connected to the compressor, and that in the movement described 100 the spring rocks on the end of the lever D, while its upper end is carried inward with the

link E and the compressor; and that any resistance which the compressor encounters from the bundle will tend to compress the spring F and cause the link E to protrude its lower end farther beyond the end of the lever D. Just before the needle reaches the limit of its upward stroke the lip B²⁰ of its tail B² collides with the end G³⁰ of the branch G³ of the dog G and rocks said dog over its pivot 10 to the position shown in dotted line in Fig. 1. The eccentricity of the edge g² of the branch G² to the pivot of the dog causes said branch bearing said edge g² against the roll D¹⁰ to force that end of the lever D downward while 15 the dog is rocked, as described, and by so doing to force the outer end of said lever upward and compress the spring F. This action occurs just at the end of the upstroke of the needle, and thereby the bundle receives an extra compression just at the last instant, and 20 the band is thereby made tighter than it would otherwise be. The tail B², however, having rocked the dog G a short distance, slips over the end of it (the difference in the centers of 25 the needle and the dog and the shorter radius of the latter permitting such result) and stands above it, acting in this movement as a ratchet-tooth engaging the dog as a pawl; but the spring G⁴, as soon as the dog is free from 30 the tail B², rocks the dog back toward its initial position, and even in the absence of the spring G⁴ the pressure of the spring F on the outer end of the lever D, causing pressure of the roller D¹⁰, on the eccentric end of the 35 branch G² of the dog G, would cause the same result, so that the needle has to recede some little distance before its tail B² comes again into contact with the end of the dog. (This is the interval in which the 40 knotter operates to form the knot.) When the tail strikes the dog, it rocks it in the opposite direction from its former movement and carries the end g² of the branch G² off the roll D¹⁰, and thereby deprives the lever D of any stop to 45 prevent its swinging on its bearing on the needle rock-shaft, and the greater weight of the arm of said lever, to which there is also added the weight of the spring F, link E, and compressor C, and the pressure and partially the 50 weight of the bundle which rests against the compressor, causes the lever to swing on its pivot and let the compressor drop out of the way of the bundle, which at this time is about to be ejected from the machine. As the needle further recedes, its back edge collides with the abutment D² on the lever D, and thereby 55 in its further recession it lifts up the lever D and restores the compressor to its initial position.

60 I am aware that heretofore the needle and compressor have been connected in their movement by means of a lever pivoted on the frame and connected to the compressor by a link which was detachable from the lever, a tripping device or dog being provided by which the needle in its recession caused the link to become detached from the lever, so that the

compressor would fall, and I do not claim such construction; but in such devices as heretofore constructed, the lever and compressor being 75 detachably and not being permanently connected, the lever could not be utilized for the purpose of communicating movement to the compressor, but served only the purpose of locking and unlocking it, whereas in the construction above set forth it is possible to actuate the compressor directly by means of the lever, which is connected permanently to it by the link E.

I claim—

1. In combination with the needle and the compressor pivoted thereto, a lever pivoted about the needle-axis, a link connecting it permanently to the compressor, a dog pivoted on the frame and engaging and forming a stop 85 for the lever, and suitable projection on the needle, whereby, when receding, it engages the dog and disengages it from the lever to permit the compressor to fall, substantially as set forth.

2. In combination with the needle and the compressor pivoted thereto, a lever pivoted on the frame and connected to and upholding the compressor, a dog pivoted on the frame and forming a stop for the lever to cause it to uphold the compressor, the needle having a projection which engages the dog when the needle recedes and causes it to release the lever and allow the compressor to fall, and the lever having an abutment which the needle at the latter part of its recession engages and thereby restores the lever and compressor to their initial position, substantially as set forth.

3. In combination with the needle, the compressor pivoted thereto and actuated thereby, 105 the lever D, pivoted about the needle-axis, the dog G, constituting a movable stop to arrest said lever, the link E, permanently connecting said lever to the compressor, and the spring F, reacting between the lever and the compressor 110 lengthwise of said link to force the lever and compressor apart, substantially as set forth.

4. In combination with the needle and the compressor connected therewith, a lever pivoted on the needle rock-shaft, a spring between 115 the compressor and the outer end of the lever, tending to force them apart, a dog pivoted on the frame and having the end g² eccentric to its pivot and forming a stop for the inner end of the lever, and the needle having the tail B², 120 engaging and rocking said dog as it advances, whereby the eccentric edge g² causes the lever D to swing toward the compressor and compress the spring between them, substantially as set forth.

In testimony whereof I have hereunto set my hand, this 8th day of July, A. D. 1886, in the presence of two witnesses, at St. Paul, Minnesota.

PAUL HANSON.
